UNITED STATES PATENT OFFICE.

JOSEPH J. MICHELS, OF SYRACUSE, NEW YORK.

RAILWAY-CAB SIGNAL.

1,360,003.

Specification of Letters Patent. Patented Nov. 23, 1920.

Application filed June 18, 1920. Serial No. 389,906.

To all whom it may concern:

Be it known that I, JOSEPH J. MICHELS, a citizen of the United States of America, and a resident of Syracuse, in the county of 5 Onondaga, in the State of New York, have invented new and useful Improvements in Railway-Cab Signals, of which the following, taken in connection with the accompanying drawings, is a full, clear, and exact 10 description.

This invention relates to certain improvements in railway cab signals adapted to be controlled by switch or semaphore operating mechanisms commonly used on railways, 15 the main object being to provide simple and efficient means for automatically operating an alarm in the engineer's or driver's cab in case an operator has failed to make the necessary adjustment of the switch or semaphore in advance of an approaching train.

In other words, I have sought to make the operation of the signal or alarm dependent upon the proper adjustment of the semaphore or switch by installing a vertically 20 movable contact member along the track in suitable relation to a semaphore or switch, and connecting said member with the operating mechanism for said switch or semaphore, so that if the switch or semaphore is 25 properly set for the safe passage of an approaching train, the signal in the cab will not be operated, while on the other hand if the switch or semaphore has not been properly set or adjusted for the safe passage of 30 a train, the movable member will cause the operation of a signal or alarm in the engineer's or driver's cab to warn him of approaching danger in time to permit him to stop the train and avoid accident.

40 Other objects and uses relating to specific parts of the device will be brought out in the following description:

In the drawings, Figure 1— is a side elevation, partly in section and partly diagrammatic of a cab signal and operating means therefor for a double or multiple track railway in which the trains generally move in one direction along certain tracks.

Fig. 2— is an enlarged detail sectional view of the upper end of the circuit closing plunger.

Fig. 3— is an enlarged sectional view taken on line 3—3, Fig. 1, showing the means for preventing the turning of the plunger.

55 In order that my invention may be clearly understood I have shown one of the rails

—1— of a railway track as resting upon suitable ties —2—, and in Fig. —1— is also shown a signal and operating mechanism therefor adapted to be operated by trains 60 moving in one direction only.

The signal or alarm mechanism is mounted in or upon the engineer's or driver's cab and comprises, in this instance, an electric bell —3— connected in an electric circuit 65 —4— to which current is supplied by a battery —5— or equivalent electric generator.

Suitable means is also provided upon the frame of the engine or in one of the cars of the train for opening and closing the bell 70 circuit, said means consisting in this instance of a tubular casing —6— secured to said frame by a clamping collar —7—, and adapted to receive a vertically movable plunger —8— which extends some distance below the lower end of the casing —6— and has its lower end provided with a roller contact member —9— for engagement with an operating member which is installed along the track as will be hereinafter more 75 fully described, the upper end of said plunger being provided with an electric conducting member —10— movable into and out of engagement with a pair of terminals —11— in the electric circuit —4—.

These terminals are preferably secured by binding posts —12— to a suitable cap —13— on the upper end of the casing —6— and are insulated from each other and from the casing to prevent short circuit, the lower ends 80 of said terminals being extended into the interior of the casing —6— in downward diverging planes to allow the conical contact member —10— to wedge between them and close the circuit when the plunger is moved 85 upwardly a sufficient distance to effect the contact, at which time, the plunger will be locked in its closed position by a sliding pawl —14— which engages in a notch —15— in the adjacent side of the plunger, thereby 90 assuring the ring of the bell until the circuit is again broken by the release of the locking means and return of the plunger.

After the engineer or driver has been sufficiently warned and brought the train to a 105 stop, the locking bolt —14— may be withdrawn from its locking position by means of a bell crank lever —16— which is connected to a cord —17— extending into the engineer's cab where it may be operated at 110 will.

If desired, an electric register —18— of

any well known construction may be connected in or to the electric circuit —4— to indicate that the signal has been operated, and also assists in placing the responsibility for accident in case the engineer or driver should fail to heed the signal.

The means for operating the plunger —8— as preferably used in connection with tracks along which the trains move in one direction only consists in this instance of a vertically movable ramp-rail or bar —19— running lengthwise of the track in a normally inclined plane and preferably hinged at one end at —20— to a suitable support case or box —21—, which in turn is secured to the upper faces of the adjacent ties —2— between the rails. The ramp-rail or bar —19— constitutes a cover for the support or box —21— and inclines upwardly from the pivot —20—, which is located at a point below the upper surface of the ball of the rail —1—, to a point some distance above said surface, in which position it is normally held by means of a spring —22— within the box —21— and having one end bearing upon the bottom of the box, and its other end engaged with the underside of the bar —19—.

The supplemental rail or bar —19— is normally inclined upwardly in the direction of movement of the train so that its free end normally lies in a plane above and in the path of the lower end of the contact roller —9—, and, if not disturbed from its normal position, will lift the plunger and cause its upper contact member —10— to contact with the terminals —11— and thereby close the circuit through the signal —3— to warn the engineer or driver of approaching danger in time to stop the train.

It is customary, however, to operate a switch or a semaphore from a distant point and in order that the engineer's signal may be employed as an additional safeguard against running into an open switch or past the semaphore signal, its action is made dependent upon the movement of the switch or semaphore operating rod, as —23—, which is connected with one arm of a bell crank lever —24—, the latter being pivoted to and within the housing support —21— and having its other arm connected by a link —25— to the free end of the supplemental rail —19— so that when the rod —23— is operated to shift the switch to a safe position for the approaching train or when the semaphore indicates safe, it will draw the free end of the supplemental rail —19— downwardly out of the path of the forwardly moving contact roller —9— through the

medium of the bell crank lever —24— and link —25—, thereby allowing the plunger —8— to remain in its normal position without operating the signal —3—, whereas, on the other hand, if the switch or semaphore should not be shifted to a safety position, the supplemental rail —19— will remain up and thereby cause the operation of the engineer's signal in the manner previously described.

What I claim is:

1. In an engineer's signaling device for railway cars an upright tube mounted on the car, a cap on the upper end of the tube, a pair of electric terminals mounted on the cap and projecting into the tube, a plunger guided in the tube and extending some distance below the lower end thereof, a roller mounted on the lower end of the plunger, an electrically operated alarm electrically connected to said terminals, a conducting ring mounted on the upper end of the plunger for contact with the terminals to close the circuit through the alarm when the plunger is elevated, and a ramp-rail along the track movable in to and out of the path of said roller for operating said plunger to cause the conducting ring to contact with the terminals when the ramp-rail is adjusted in the path of the roller.

2. In an engineer's signaling device for railway cars, an upright tube mounted on the car and having its upper end provided with a cap, a pair of electric terminals mounted on the cap and projecting into the tube in downwardly diverging planes, an electric alarm, electrically connected to said terminals, a plunger movable in the tube and having its lower end projecting some distance below the lower end thereof, a contact part on the lower end of the plunger, a conducting ring on the upper end of the plunger movable into and out of contact with said terminals as the plunger is raised and lowered for closing the circuit through the alarm when the plunger is raised, and a ramp-rail along the track for engaging the contact part on the lower end of the plunger and raising said plunger to bring its contact ring into contact with said terminals, and means for locking and releasing the plunger in and from its raised position.

In witness whereof I have hereunto set my hand this 15th day of June 1920.

JOSEPH J. MICHELS.
